UNITED STATES PATENT OFFICE.

JESSE O. WELLS, OF DES MOINES, IOWA.

AUTOMATIC CIRCUIT-CLOSER FOR ELECTRIC FIRE-ALARMS.

SPECIFICATION forming part of Letters Patent No. 277,965, dated May 22, 1883.

Application filed January 29, 1883. (No model.)

To all whom it may concern:

Be it known that I, JESSE O. WELLS, of Des Moines, in the county of Polk and State of Iowa, have invented an Automatic Circuit-Closer for Electric Fire-Alarms, of which the following is a specification.

The object of my invention is to save life and property from fire by providing a means for automatically closing the circuit in an electric fire-alarm as required to ring a bell or series of bells when a fire originates and the temperature rises in any part of a building in which wires are located for electric-alarm purposes.

It consists in combining an auxiliary metal spring with the armature of a push-button circuit-closer and insulating it by means of fusible matter, as hereinafter fully set forth, in such a manner that when the temperature rises sufficiently to fuse the insulating material the force of the auxiliary spring will be exerted to automatically perform the function of a push-button in closing the circuit as required to signal and alarm by ringing a bell in an office or station, or a series of bells located in a corresponding series of rooms or stations in a building.

Figure 1 of my accompanying drawings is a top view of the uncovered base of a push-button to which my insulated auxiliary spring is attached. Fig. 2 is a top view of the cover. Fig. 3 is a half-section of a complete push-button and circuit-closer having my auxiliary insulated spring attached. Together these figures clearly illustrate the construction and operation of my complete invention.

a represents the wooden base of a push-button of common form.

b is a raised center, that has a screw-thread on its periphery.

c is a curved metal plate, fastened on top of the raised portion *b* in such a manner that it will extend from its circumference to the center.

d is a metal spring-plate, fixed on the opposite side of the center of the same raised sur-

face *b* in such a manner and position relative to the plate *c* that the free end of the spring will in its normal condition extend over the inner end of the plate *c*, and overlap and engage it when pressed down by means of the button

placed on top of it.

Nos. 1 and 2 represent wires connected with

the armature-plates *c* and *d* by means of pins *f*, that extend through the base *a*, and are fixed to the armature-plates, or in any suitable way.

g represents my auxiliary metal spring, fixed 55 on top of the base *b* and plate or spring *d* by means of screws, or in any suitable way. It may be made of wire or sheet metal, and vary in form; but it is essential that its free end *g'* extend over the outer position or end of the 60 fixed armature-plate *c* in such a manner that it will, in its normal condition, press upon the plate *c* and form a connection between the two plates *c* and *d* and the two wires Nos. 1 and 2, as required to establish an electric circuit. 65

h represents a piece of wax or other suitable matter that will fuse at a low degree of heat, and that is a non-conductor, placed between the plate *c* and the free end of my auxiliary spring to retain it elevated and insulated. 70

k is a cup-shaped cover, adapted to fit upon and screw fast to the base *a* in a common way.

3, 4, and 5 represent perforations through the cover, to allow heat to enter and melt the wax *h*. 75

6 is an opening in the center of the cover, through which a button, *m*, projects upward from the free end of the spring *d*, upon which the bottom of the button rests.

In the practical operation of my improved 80 circuit-closer the complete push-button is applied in a common way and operated at pleasure by simply pressing upon the button *m* to close the electric circuit for the purpose of making a call-signal or to give an alarm; and 85 whenever a fire occurs close enough to the button to cause the wax or insulating material *h* to fuse, my auxiliary spring and circuit-closer will assume its normal position and form a connection with the plate *c* and establish a circuit between the two plates *c* and *d* and the wires Nos. 1 and 2, to automatically perform the function of an operator in giving an alarm when the occupants of the room or building may be asleep or absent. 90

I am aware that easily-fusible alloys have been combined with electric fire-alarms and circuit-closers in such a manner that a rise of temperature caused by fire would melt the fusible matter, and thereby connect or break electric circuits to automatically operate alarm mechanisms. I am also aware that a bar com- 95 100

posed of two metals has been coiled within and fixed to a push-button circuit-closer in such a manner that a rise of temperature would cause the free end of the coiled bar to move and automatically close an electric circuit; but my manner of combining an auxiliary spring with a push-button and retaining the spring inoperative by means of fusible matter until the heat of an incipient fire will release it and allow it to resume its normal position, and in so doing automatically close or establish an electric circuit and operate an alarm, is novel and greatly advantageous.

I claim as my invention—

In a push-button circuit-closer, the combination of a plate, *c*, having a conducting-pin *f* attached, a spring-plate, *d*, having a conducting-pin *f* attached, an auxiliary spring, *g*, and a fusible insulator, *h*, substantially as shown and described, to operate in the manner set forth, for the purposes specified. 15

JESSE O. WELLS.
